CLAIM

The ornamental design for a variable cable connector interface for data processing equipment, as shown and described.

DESCRIPTION

FIG. 1 is a bottom perspective view of a variable cable connector interface for data processing equipment embodying my new design;

FIG. 2 is a top perspective view thereof;

FIG. 3 is a top view thereof; and

FIG. 4 is a side view thereof.

FIG. 1

FIG. 2

FIG. 3

FIG. 4
